UNITED STATES PATENT OFFICE.

COE SMITH GARDNER, OF DE LAND, FLORIDA, ASSIGNOR OF ONE-HALF TO GEORGE H. FOOTE, JR.

AIR-PUMP ATTACHMENT.

1,212,760.

Specification of Letters Patent. Patented Jan. 16, 1917.

Application filed June 28, 1913. Serial No. 776,331.

To all whom it may concern:

Be it known that I, COE SMITH GARDNER, citizen of the United States, residing at De Land, in the county of Volusia and State of Florida, have invented certain new and useful Improvements in Air-Pump Attachments, of which the following is a specification.

This invention relates to an improved air pump of the rectilinear manually operated type, and the primary object thereof is to provide means for facilitating the downward or compression stroke of the piston to force the air into a tire in connection with which pumps of this character are commonly used.

Heretofore, during the inflation of tires, it has been impossible to carry out the full downward or compression stroke of manually operated pumps owing to the fact that the air pressure within the tire offers sufficient resistance to the pump piston to prevent a full stroke thereof, thus rendering the desired full inflation of the tire impossible.

It is therefore an object of my invention to overcome the above and various other objectionable features and to provide an attachment or device adapted to be employed in connection with an ordinary rectilinear manually operated pump whereby the power of the downward stroke is materially increased, thereby permitting a full and complete stroke of the pump piston regardless of the air pressure within the tire, this being accomplished by means of a plurality of specially arranged levers and other elements adapted to be disposed in such a novel and peculiar manner as to substantially increase, and in fact double the leverage necessary for the inflation of tires in the desired manner.

The invention still further resides in the provision of means adapted to be operated by the pump handle to force the piston downwardly within the cylinder provided therefor, thereby permitting a full compression stroke during the application of the invention.

The above and additional objects are accomplished by such means as are illustrated in their preferred embodiment in the accompanying drawings, described in the following specification and then more particularly pointed out in the claims which are

appended hereto and form a part of this application.

In describing my invention in detail reference will be had to the accompanying drawings wherein like characters denote like or corresponding parts throughout the several views, and in which:—

Figure 1 is a side elevation of an ordinary manually operated air pump with the device or attachment arranged thereupon; Fig. 2 is a similar view illustrating the position of the several parts during the downward stroke of the piston; Fig. 3 is a similar view illustrating the position of the several parts, the stroke nearing its completion; Fig. 4 is a similar view illustrating the position of the several parts after the stroke has been completed; and Fig. 5 is a rear elevation of the pump as illustrated in Fig. 4.

Referring now to the drawings, the numeral 1 designates an ordinary rectilinear manually operated air pump comprising the usual cylinder 2, base 3 and piston rod 4, the latter projecting from the exterior of the cylinder for the purpose of guiding the handle 5 which is slidably arranged thereupon. Pivotally secured upon each side of the handle 5 is a connecting lever 7, the opposite end of the lever being hingedly connected as at 8 to a reciprocatory bell crank block 9, the latter being pivotally secured as at 10 to a sliding block 11 mounted upon a vertically extending rod 12 disposed adjacent the cylinder 2 and extending in parallel spaced relation thereto. A stationary block 13 is secured to the piston rod 4 below the handle 5, the block having rods 14 depending from each side thereof, the opposite ends of the rods 14 being pivotally secured as at 15 to the reciprocatory blocks 9 so that the reciprocatory movement imparted to the said blocks will be in turn transmitted to the piston rod 4.

The block member 11 to which the bell crank blocks 9 are pivotally secured is provided with a catch member 16 adapted to be normally forced into engagement with the rod 12 through the medium of a leaf spring 17 carried by the said block and engaging the said catch, this arrangement of the spring forcing the catch into a notch 18 provided therefor within the rod 12 after the block members 9 have been slid until the blocks 11 engage an enlargement 19 formed at the base of the rod 12. Any suitable

means such as a bracket designated by the numeral 20 may be employed for the purpose of supporting the rod 12 in parallel spaced relation to the cylinder 2, the opposite end of the said rod from that engaged by the bracket being fixedly secured to the base 3 of the pump. The handle 5 when raised to its uppermost position draws the bell crank blocks 9 toward the top of the cylinder 2, the said blocks having a bar 21 extending from one to the other thereof to limit the upward movement thereof, the bar engaging the rods 14 and retaining the connecting levers 7 at a slight angle to the piston rod 4. The lever 7 being slightly off center as is clearly shown in Fig. 1 of the drawings it will be seen that the downward movement of the handle will cause the blocks 9 to slide vertically until the block 11 to which the said blocks are connected engages the enlargement 19 of the guide rod 12, in which event a continued downward movement of the handle 5 will cause the blocks 9 to swing upon the pivotal connection 10 as is clearly shown in Fig. 3, such swinging movement forcing the rods 14 to continue their downward stroke until the said blocks 9 assume the position illustrated in Fig. 4 whereupon the block 13 to which the rods 14 are connected engages the upper extremity of the cylinder 2 thereby completing a full stroke of the cylinder piston. As the blocks 9 are slid vertically upon the cylinder 2 and rod 12, until the block 11 engages the enlargement 19, the catch 16 is forced into the notch 18 provided therefor by means of the pressure brought to bear upon the said catch through the medium of the spring 7, such engagement preventing a reverse vertical movement of the block 11 and locking the said block immovable upon the rod 12. After automatically locking the block 11 as above described, the continued downward pressure upon the handle 5 will cause the bell crank blocks 9 to swing outwardly or away from the said block thereby drawing the piston rod 12 to which the said blocks are connected, downwardly, the arrangement of the rods 14 which connect the bell crank blocks to the piston 4 causing the said piston rod to be drawn downwardly until the block 13 engages the upper end of the cylinder thereby permitting a full stroke of the cylinder piston. Extensions 22 are formed upon each side of the catch member 16, the said extensions adapted to be engaged by the block 9 during the upward stroke of the piston, such engagement forcing the catch out of engagement with the notch 18 and allowing the blocks 9 and 11 to extend or move upwardly until they again assume the position illustrated in Fig. 1 whereupon the pump is ready for a second compression or downward stroke.

It will be seen from the above, taken in

connection with the accompanying drawings that the catch member 16 is automatically thrown into and out of engagement with the notch 18 provided therefor by the action of the spring 17 and bell crank blocks 9; that the leverage or pulling power generated by the novel and peculiar arrangement of the bell crank blocks and rods 14 is sufficient to force the piston rod 14 downwardly until the block 13 engages the upper extremity of the cylinder, and the piston carried by the said rod completes its downward stroke; and that the moment the block 11 engages the enlargement 19 of the guide rod 12, the bell crank blocks begin to swing upon their pivot point 10 causing the said blocks 9 to pull downwardly upon the piston rod until the stroke thereof is completed.

In reduction to practice, I have found that the form of my invention, illustrated in the drawings and referred to in the above description as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:

1. The combination with a pump body and a piston structure therefor, means for moving said piston structure comprising a reciprocally mounted handle, a power increasing element, and means pivotally connecting said piston to said handle through said power increasing element.
2. In combination, a pump body and a piston structure therefor, manual means for moving the piston structure toward a final pumping position, slidably supported mechanism connected with the piston structure and actuated by the operating means for increasing the manual thrust applied by said means as the piston structure approaches a final pumping position.
3. In combination, a pump body, and a piston structure therefor, means for moving said structure, bodily reciprocating mechanism movable with said means, stop means to limit movement of said mechanism, and means connecting said mechanism with said first mentioned means to increase the thrust on said structure by a continued movement of said means.
4. In combination, a pump body and a piston structure therefor, means for moving said structure, mechanism movable bodily with said means, guide means for said mechanism, stop means to limit the movement of said mechanism, and means

connecting said mechanism with said first mentioned means to increase the thrust on said structure by a continued movement of said means.

5. In combination, a pump body, and a piston structure therefor, operating means for said piston structure, mechanism movable bodily according to the movement of said operating means, guide means for said mechanism, means for limiting the movement of the said mechanism as the piston structure approaches a final pumping position, and means connecting said mechanism with said operating means, said last mentioned means adapted to actuate said mechanism by a continued movement of said operating means to increase the thrust on said piston structure.
6. In combination, a pump body and a piston structure therefor, operating means for said structure, mechanism bodily movable according to the movement of said operating means, the length of stroke of said mechanism being shorter than the stroke of said piston structure, guide means for said mechanism, and means connecting said operating means to said mechanism, the said last mentioned means adapted to actuate the said mechanism by a continued movement of the piston structure to increase the thrust applied thereto.
7. In combination, a pump body, and a piston structure therefor, operating means for said piston structure, a bodily movable operating lever, said lever being movable according to the movement of said piston structure, means connecting said lever with said piston, means connecting said lever with said operating means, means for guiding said lever, stop means to limit the bodily movement of said lever, the said lever when stopped by said last mentioned means adapted to be actuated by a continued movement of said piston structure to increase the thrust applied thereto, as and for the purpose set forth.
8. In combination with an air pump having a piston rod projecting from one end thereof, a handle slidably mounted upon said rod, a guide bar and lever means carried by the said bar adapted to be operated through movement of said handle to increase the thrust applied to said rod, as and for the purpose set forth.
9. In combination with an air pump having a piston rod projecting from one end thereof, a handle slidably mounted upon said rod, a guide bar rigidly secured to the said pump and extending parallel with the cylinder thereof, a block slidably mounted upon the said bar, and means connecting the said block to the said handle for imparting motion thereto, as and for the purpose set forth.
10. In combination with an air pump hav-
- ing a piston rod projecting from one end thereof, a handle slidably mounted upon said rod, a guide bar rigidly mounted adjacent the pump, a block slidably mounted upon the said rod, and means including bell crank blocks pivotally secured to the said sliding block and connected to the said handle for sliding the said block throughout the length of the bar, as and for the purpose set forth. 75
11. In combination with an air pump having a piston rod projecting from one end thereof, a handle slidably mounted upon said rod, a guide bar, a block slidably mounted upon the said bar, means connecting the said sliding block to the said handle, and means connected to the piston rod adapted to be operated by the said handle, as and for the purpose set forth. 80
12. In combination with an air pump having a piston rod projecting from one end thereof, a handle slidably mounted upon said rod, a guide bar, a block slidably mounted upon the said bar, means for locking the said block against vertical movement upon the said rod, and means carried by the piston rod adapted to be connected to the said block and the said handle for operating the piston according to the movement of the handle, as and for the purpose set forth. 85
13. In combination with an air pump having a piston rod projecting from one end thereof, a handle slidably mounted upon said rod, a guide rod, a block slidably mounted upon the said rod, a lever pivotally secured to the said handle having the other end hingedly connected to the said bell crank blocks, and means including rods connecting the said bell crank blocks with the said piston rod for operating the latter according to 90 the movement of the handle. 95
14. In combination with an air pump having a piston rod projecting from one end thereof, a handle slidably mounted upon said rod, a vertically extending guide bar arranged adjacent the said pump, a block slidably mounted upon the said rod, means for limiting the movement of the said block, bell crank blocks pivotally secured to the said sliding block, the said bell crank blocks being in turn connected to the said handle, rods connecting the said bell crank blocks to the said piston rods, the said bell crank blocks adapted to be swung from their point of pivotal connection to the said guide block 110 by the operation of the handle for operating the piston rod, as and for the purpose set forth. 115
15. In combination with an air pump having a piston rod projecting from one end thereof, a handle slidably mounted upon said rod, a guide bar adapted to extend parallel with the said pump and in spaced relation thereto, a vertically slidable block mounted upon the said guide bar, an enlargement 120
- 130

- formed at the base of the said rod for limiting the downward movement of the said block, means for automatically locking the said block against upward movement when in engagement with the said enlargement, bell crank blocks pivotally secured to the said slideable block, levers connecting the said bell crank blocks to the said handle, and rods connecting the said bell crank blocks to the said piston rod for operating the latter by swinging the bell crank blocks upon their pivotal connection to the said slideable block according to the operation of the said handle, as and for the purpose set forth.
- 15 16. In combination with an air pump having a piston rod projecting from one end thereof, a handle slidably mounted upon said rod, a guide bar carried by the said pump adapted to extend in parallel spaced relation thereto, a vertically slideable block carried by the said guide bar, an enlargement formed at the base of the said guide bar for limiting the downward movement of the said pump, a spring pressed catch member carried by the said block adapted to engage a notch formed within the said bar for locking the said block against upward movement when in engagement with the said enlargement, bell crank blocks pivotally connected to the said slideable blocks, levers connecting the said bell crank blocks to the said handle, means for limiting the pivotal movement of the said bell crank blocks, and

means including rods connecting the said piston rod to the said bell crank blocks for operating the said piston rod and swinging the bell crank blocks from their pivotal connection with the said slideable blocks according to the operation of the said handle, as and for the purpose set forth.

17. In combination with an air pump having a piston rod projecting from one end thereof, a handle operable upon said rod, a guide bar, motion transmitting means interposed between said handle and the piston rod, to increase the thrust applied through said handle to the rod as the latter reaches a final pumping position.

18. In combination with a pump body having a piston rod projecting from one end thereof, a handle operable on said piston and independently thereof, a guide bar adjacent said pump body, lever mechanism having pivoted engagement with said pump rod and said handle and slideable and pivoted engagement with said guide bar forming a fulcrum for increasing the thrust on the piston rod, and means for limiting, at times, the reverse movement of said fulcrum.

In testimony whereof I affix my signature in presence of two witnesses.

COE SMITH GARDNER.
